J. J. REINHOLD

INTERNAL COMBUSTION ENGINE

Filed Nov. 14, 1921

INVENTOR
John J. Reinhold,
BY
Bernard C. Becker,
ATTORNEY

UNITED STATES PATENT OFFICE.

JOHN J. REINHOLD, OF MARIETTA, PENNSYLVANIA.

INTERNAL-COMBUSTION ENGINE.

Application filed November 14, 1921. Serial No. 514,977.

To all whom it may concern:

Be it known that I, JOHN J. REINHOLD, a citizen of the United States, and a resident of Marietta, county of Lancaster, State of Pennsylvania, have invented certain new and useful Improvements in Internal-Combustion Engines, of which the following is a specification.

This invention relates to internal combustion engines of the multiple cylinder type, wherein the inlet ports of a number of cylinders are connected to a common manifold which supplies the fuel.

The object of this invention is to provide means whereby high efficiency can be maintained throughout the life of the engine; or in other words to provide means whereby a practical perfect fuel mixture is obtained in each cylinder under changing conditions.

This invention will be more fully understood by taking into consideration the following conditions which exists at various periods during the life of an automobile engine:—When the engine is new the piston and piston rings fit properly, and the manifold and carburetter proportions are correct to suit these conditions, the engine has great power and runs smooth; but, when the pistons and piston rings wear and become leaky, oil from the crank case enters the combustion chamber and the efficiency of the engine is reduced, unless adjustment is made to the carburetter.

It is obvious that all the pistons on a multiple cylinder engine will not wear at the same rate, therefore all the cylinders will not receive the same quantity of oil from the crank case and the carburetter cannot be adjusted to accommodate this condition in all the cylinders. The result is that all the cylinders will not operate at their highest efficiency.

To correct the fuel mixture I provide an automatic inlet valve which permits air or some other tempering fluid to enter directly into the combustion chamber of each cylinder, and also means whereby the quantity of air or tempering fluid which enters each cylinder may be regulated; and further I provide means whereby the combustion of the fuel can be observed. With this combination the fuel mixture of each cylinder can be controlled and regulated whereby complete combustion of the fuel takes place.

Fig. 1, represents a longitudinal sectional

view of a device which discloses one form of my invention.

Fig. 2, represents an internal combustion engine with devices like shown in Fig. 1 attached thereto.

1 indicates a sectional view of a portion of one of the cylinders 30 of an internal combustion engine 31, the same being provided with a hole 2 which leads directly to the combustion chamber of the engine. 3 is a valve casing which is screwed into the threaded portion 4 of the hole 2. The casing 3 carries a hexagon shaped portion 5 to fit a wrench.

Formed in the casing 3 is a valve chamber 6 and a valve 9, which is free to slide and adapted to close the valve seat 7 through the valve head 10. Forming part of the valve 9 and the valve head 10 is a valve stem 17, the same being provided with a hole 11 throughout its entire length as shown.

To the end of the valve stem 17 is screwed the cap 14 which clamps a glass disk 15 over the hole 11 and thereby closing the same. A hole 16 is provided in the cap 14.

It is apparent that vision may be had to the combustion of the fuel by looking through the hole 16, glass disk 15, hole 11, valve chamber 6 and hole 2 into the combustion chamber.

The valve head 10 is normally held against the valve seat 7 through the spring 18, set collar 19 and valve stem 17; the set collar 19 being alterably fixed to the valve stem 17 through the set screw 20. It is obvious that adjustment may be made to the spring pressure by shifting the set collar 19 on the valve stem 17.

The casing 3 is provided with an extension 21, having openings 22 for ventilating the spring 18 so that it does not get hot enough to anneal from the heat of the engine. Screwed into the case extension 21 is a valve stem guide 23 which also acts as a stop for the valve movement when the nut 24 comes in contact therewith.

In the upper end of the casing 3 is a chamber 25 which communicates with the bore 8, and from which leads the pipe 26. The valve 9 is provided with openings 27 which form communication between the chamber 25 and the chamber 6 when the valve is open as shown.

The operation of this device is as follows:

For illustration assume that a device of the kind as represented in Fig. 1, is placed on each of the cylinders of a two cylinder engine 31; and a single carburetter 32 regulates the fuel mixture which enters a manifold 33 which connects with the inlet ports of both cylinders.

This device on both cylinders is first made inoperative by turning down the nut 24, 10 thereby drawing the valve head 10 tight on the valve seat 7. The engine is now started and the carburetter is adjusted in the usual manner to a point where the best results are obtained. Now an observation is made to 15 determine in which of the two cylinders complete combustion is obtained; this may readily be determined by the color of the flame, for instance, a red flame indicating incomplete combustion and a blue flame indicating complete combustion. It is probable that the cylinder with the red flame is getting the most oil from the crank case.

Now the object is to temper the mixture in the combustion chamber of the cylinder, 25 with the red flame, this is accomplished by releasing the nut 24 and thereby permitting the valve 9 to be drawn open by the vacuum in the combustion chamber during each suction stroke. When the valve 9 is open, 30 air is drawn into the combustion chamber through the pipe 26, chamber 25, openings 27, chamber 6 and hole 2, thereby reducing the vacuum and cutting down the quantity of fuel mixture drawn from the manifold.

35 The quantity of air drawn through the opening 27 may be regulated by controlling the amount of movement of the valve 9; for instance, the area of the orifice of the opening 27 will be more or less depending upon 40 the amount of movement of the valve 9; this will be apparent by referring to the drawing where the valve is shown to be open to the extent indicated between the arrows 28,

and if the valve is moved further down the opening will be greater, or vice versa.

The extent to which the valve 9 can open 45 may be regulated by adjusting the nuts 24 and 29 on the valve stem 17.

If at any time it is desired to put this device in inoperative condition without disturbing the nuts 24 and 29, the same may be accomplished by unscrewing the valve stem guide 23 until the same raises sufficiently to bear against the nut 24 and pulls the valve head 10 hard on the valve seat 7, 55 under which condition no air can enter or leave the combustion chamber through this device.

It is obvious that the pipe 26, instead of being open to the air, might be connected 60 to the top of the radiator chamber where it will suck water vapor or steam as well as air, or it may be connected to a reservoir of some other kind of tempering fluid.

It is to be understood that this invention 65 is not limited to any specific construction as it is obvious that numerous modifications might be made without changing the nature and scope of this invention.

Having thus described my invention, what 70 I claim and desire to secure by United States Letters Patent is as follows:

The combination with an internal combustion engine having more than one cylinder, 75 of a fuel supply for the cylinders, a manifold for conducting the fuel supply to two or more cylinders, means for admitting directly in each cylinder a tempering fluid to bring the fuel mixture to a practical perfect state, means for independently controlling 80 the quantity of said tempering fluid which enters each cylinder, and means provided whereby combustion of the fuel is visible.

In testimony whereof I affix my signature.

JOHN J. REINHOLD.
